LOOM TEMPLE

Thomas Hindle, Blackburn, England

Application September 28, 1949, Serial No. 118,254
In Great Britain October 7, 1948

5 Claims. (Cl. 139—301)

1

This invention relates to looms for weaving and more particularly to improvements in means for supporting the temples on the loom front-rest.

The main object of the invention is to provide improved means for supporting the temples, whereby these may be conveniently adjusted as requirements may necessitate in relation to the reeded width, to the level of the cloth at the fell and to the fell of the cloth, and then be rigidly secured so as effectively to resist the heavy contractual pull of the cloth during the weaving process.

Another object is to provide improved means whereby the temple and its holder-bar are promptly released and allowed to move forward quite freely, so avoiding damage to the parts involved in the event of any object, such as a shuttle, being accidentally trapped between the temple and the advancing reed.

A further object is to provide improved means whereby the temples, after these have been manipulated in the usual manner to engage the selvedges of the cloth, are forcibly drawn outwards towards the end of the loom until the fell of the cloth is extended to its full reeded width, after which the aforesaid temple supporting means are firmly secured so as to maintain such width adjustment.

According to the invention each temple is carried at the end of a temple holder bar in which it can be adjusted vertically, the holder bar is adjustably mounted in a clamp stand so that the rear edge of the temple can be set closely adjacent to but in front of the fell line of the cloth and the clamp stand is slidably mounted on a longitudinal rail whereby the clamp stand and with it the holder bar and the temple can be set in any desired position corresponding with the reeded width and locked in such position by set screws.

The invention is illustrated in and will be described with reference to the accompanying drawings in which:

Fig. 1 is a partial front elevation showing the front-rest and temple supporting means at the left end of a loom;

Fig. 2 is a plan corresponding to Fig. 1;

Fig. 3 is a vertical section on line 3—3 of Fig. 1; and shows the temple in its normal position;

Fig. 3a is a detail plan of the temple holder-bar and its clamping-stud;

Fig. 3b is a partial vertical section on line 3b—3b of Fig. 1, and shows the pulling clamp;

Fig. 4 is a view similar to Fig. 3, but shows the temple and its holder-bar after these have been released and carried forward by an obstruction between the temple and the reed.

Referring to Figs. 1, 2 and 3, the front-rest of the loom consists of the horizontal flat section 1 and the vertical flat section 2, both of which are suitably secured by bolts or setscrews to

2

the end-frame F at each end of the loom, also to any number of intermediate frames F¹. In some cases, the flat sections 1 and 2 are tack-welded together to ensure mutual support and stiffness.

An additional member or temple rail 3 is mounted on and firmly attached, preferably by welding, to the horizontal flat section 1, and this combination of the three sections 1, 2 and 3, while avoiding excessive weight and unduly large overall cross-sectional dimensions, provides a front-rest of exceptionally strong and rigid construction, such as is essential in the case of heavy and/or wide looms.

As shown by dotted lines at C in Fig. 3, the woven cloth moves forward from the fell, the position of which is indicated by line f—f, over the cambered top-edge of the temple rail 3 and downward over the rounded front edge of the flat section 1 to the usual take-up roller (not shown).

The temple rail 3 is preferably grooved on both its front and rear vertical faces as shown at 3a, although the groove on the front face may be omitted, if desired, without serious detriment. The said groove or grooves may extend the full length of the temple bar or may be restricted in length to a suitable distance from each end.

Considering one end of the loom as shown in Figs. 1 and 2, a clamp stand 4 is adapted to straddle and engage the grooves in the temple rail 3 on which the clamp stand is a sliding fit, but is clamped thereto by setscrews 5 in any desired position according to the reeded width.

A cover-plate 7 is adjustably secured by screws 4a to the top of the clamp stand 4. The underside of the cover-plate 7 and the top face of the stand 4 are grooved to provide in combination a tapered slot corresponding to the tapered shank of a temple holder-bar 6, which is a slideable fit in the said slot.

The temple holder-bar 6 is rectangular in cross section, the vertical faces being parallel as shown in Figs. 1 and 2. The underside is horizontal and the top face is tapered as shown at 6a in Figs. 3 and 4.

The temple 8 may be of any known form, but is characterized by having a vertically projecting shank 9, by which it is supported. This shank 9 has a sliding fit in a vertical hole 10 bored in the rearwardly projecting end of the holder-bar as shown in Fig. 3a; and is clamped therein by a clamp stud 11.

Before tightening the clamp-stud 11, the height of the temple relative to the level of the cloth at the fell is conveniently adjusted by means of a screw 12, which screws into the top end of the temple shank 9, while the screw head bears on the hollow cap 13 which itself stands on the holder-bar 6. After suitable height ad-

justment has been effected in this manner, the rear edge of the temple is set parallel to the fell line $f-f$ as shown in Fig. 2, and the clamp-stud 11 is then tightened to lock the temple to the holder-bar.

The cover-plate 7 is adjusted by means of its screws 4a to permit the holder-bar 6 to project to the extent necessary to place the rear edge of the temple closely adjacent to, but in front of, the fell line $f-f$. The screws 4a are not simply tightened down to clamp the holder-bar, but are adjusted so that the holder bar 6 complete with its temple 8, may be pushed into the desired position by hand, when the wedging action of the tapered profile of the holder bar 6 in the 15 tapered slot formed in the clamp stand 4 and associated cover-plate 7 suffices to retain the parts in the normal weaving position shown in Fig. 3.

In the event of pressure being applied to the 20 temple as indicated by the arrow A¹ in Fig. 4, the wedge-shaped holder-bar is instantly and readily released and displaced in the forward direction as indicated by the arrow A², which free sliding movement avoids damage to any of 25 the parts involved.

After such releasing action, the temple may be restored to its working position, shown by Fig. 3, either by hand, or with the aid of a mallet applied to the front end of the temple holder-bar 6. 30

When commencing weaving, either initially or after unweaving to eliminate a fault, the screws 5 are released and the stand 4 then moved in towards the centre of the loom to facilitate engagement of the temple rings with the cloth. To enable the temple and its supporting stand to be returned readily to its working position, a pulling screw 14 is temporarily screwed into the stand 4 and a pulling clamp 15, carrying the screw 14 is fitted on and clamped by its set-screws 15a to the temple rail 3, as shown in Figs. 1, 2 and 3b. By the use of a key to turn nut 14a, the pulling screw 14 is pulled through the stationary pulling-clamp, and consequently the stand 4 together with the holder-bar 6 and temple 8 is forcibly pulled out (preferably simultaneously at each end of the loom) until the cloth width at the fell is equal to and in alignment with the reeded width, after which operation the screws 5 are again tightened to retain the stand 40 4 and the parts carried thereby, in such position.

If desired, the pulling-clamp and pulling screw may be retained permanently in situ as shown in Figs. 1 and 2.

The temple rail 3, stand 4, holder-bar 6 temple 55 8 with its characteristic vertical shank 9 and its means for height adjustment comprising the screw 12 and cap 13, may be applied to looms in which the front-rest construction is different from that hereinbefore described. For instance, the temple rail 3 may be made of greater depth and bolted or otherwise secured to the inner vertical face of a timber and/or metallic front rest. Alternatively, the temple rail 3 may be attached by welding or otherwise, to a plate or plates corresponding to the flat section 1, and such plate or plates, bolted or otherwise secured to a timber and/or metallic front-rest.

I claim:

1. Means for supporting a temple on the front rest of a weaving loom comprising a temple, a clamp stand, and a temple holder bar rectangular in cross section, the vertical faces being parallel, the under surface being horizontal and the top surface inclined rearwardly and the clamp stand

being formed with a correspondingly shaped tapered slot through which the holder bar passes whereby when the holder bar is moved rearwardly through the tapered slot it will be held sufficiently tightly to withstand any normal force tending to displace it during the normal running of the loom, but should any abnormal force be applied to the temple, such as caused by a shuttle being trapped between the temple and the advancing reed, the holder bar will be instantly released and displaced in a forward direction.

2. Means for supporting a temple on the front rest of a weaving loom comprising a temple, a clamp stand, and a temple holder bar rectangular in cross section, the vertical faces being parallel, the under surface being horizontal and the top surface inclined rearwardly and the clamp stand being formed in two parts with a tapered slot between them with means for adjusting the distance between the two parts to vary the depth of the tapered slot through which the holder bar passes whereby when the holder bar is moved rearwardly through the tapered slot it will be held sufficiently tightly to withstand any normal force tending to displace it during the normal running of the loom, but should any abnormal force be applied to the temple, such as caused by a shuttle being trapped between the temple and the advancing reed, the holder bar will be instantly released and displaced in a forward direction.

3. Means for supporting the temples on the front rest of a weaving loom, comprising the combination of a temple holder bar having a vertical hole therein, a temple having a vertical shank slidably fitting the hole in the temple holder bar, means for clamping the shank of the temple in any desired position in the hole in the temple holder bar, a clamp stand in which the temple holder bar is mounted adjustably so that the rear edge of the temple can be set closely adjacent to but in front of the fell line of the cloth being woven, a longitudinal temple rail on which the clamp stand is slidably mounted to set the temple holder bar and the temple in any desired position corresponding with the reeded width of the cloth, and means for locking the clamp stand at the desired position on the temple rail.

4. Means for supporting the temples on the front rest of a weaving loom as defined in claim 3, including means for adjusting the shank of the temple vertically in said vertical hole in the temple holder bar and thereby adjusting the height of the temple.

5. Means for supporting the temples on the front rest of a weaving loom as defined in claim 3, including means for moving the clamp stand on the temple rail to bring the temple into its normal working position.

THOMAS HINDLE.
